Patented May 9, 1922.

UNITED STATES PATENT OFFICE.

JULIA E. RISTY, OF PIPESTONE, MINNESOTA.

CHICKEN COOP.

1,415,397.

Specification of Letters Patent.

Patented May 9, 1922.

Application filed April 22, 1921. Serial No. 463,455.

To all whom it may concern:

Be it known that I, JULIA E. RISTY, a citizen of the United States, residing at Pipestone, in the county of Pipestone and State 5 of Minnesota, have invented certain new and useful Improvements in Chicken Coops; and I do declare the following to be a full, clear and exact description of the invention, such as will enable others skilled in the art to 10 which it appertains to make and use the same.

This invention relates to improvements in chicken coops of the type wherein it is desired to confine the mother hen, yet permit 15 the chicks to roam at large, thus overcoming the possibility of the hen stepping on and killing the small chicks as is a common occurrence, especially when confined in the usual housing or coop.

20 The principal object of the invention is to provide an improved coop of this type which embodies an inner compartment in which the hen is to be confined and an outer compartment which surrounds the first-named compartment and provides between 25 its inner face and the latter, a runway for the small chickens, said outer compartment being formed at its bottom with a plurality of openings through which the chickens can 30 pass in and out.

Another object of the invention is to provide a coop embodying the aforesaid compartments, the inner one being of such construction that it effectively confines the hen, 35 yet permits the chicks to enter the same at any point around its periphery.

Another and very important object of the invention is to provide a coop embodying the aforesaid construction, the compartments being formed with oppositely disposed or aligned outlet openings closed by 40 doors, there being two doors closing the opening in the inner compartment and these doors being hinged and of such a size that 45 when they are swung open, they serve to close the aforesaid runway so that the hen cannot get into the latter.

Still another object of the invention is to provide a novel brooder for chickens 50 which is provided at its top with an opening by means of which access may be had to the interior of the coop, this opening being surrounded by a rim having air inlet openings therein, the opening in the top of the 55 coop being closed by a cover which is

equipped with a depending apertured flange surrounding said rim, whereby when the cover is rotated, the inlet openings may be opened or closed as the case may be.

Other objects and advantages of the invention will be apparent during the course of the following description.

In the accompanying drawings forming a part of this specification and in which like numerals are employed to designate like parts throughout the same:

Figure 1 is an elevational view of an improved coop constructed in accordance with this invention.

Figure 2 is a horizontal sectional view 70 taken on the plane of the line 2—2 of Fig. 1.

Figure 3 is a vertical sectional view of a portion of the coop.

Figure 4 is a detail view showing the 75 closure for the openings at the bottom of the coop.

Referring to the drawings by numerals, 1 designates an inner compartment composed of spaced wires or the like, the same 80 being intended, as before suggested, to confine the mother hen therein. This inner compartment is substantially circular in shape and is surrounded by a sheet metal housing or outer compartment 2 which is 85 spaced from the inner compartment in such a way as to provide a runway 3 for the small chicks. At this point, I wish to state that the inner compartment may be made from slats or may be constructed in any other 90 way. However, I wish to construct it in such a way that it will effectively confine the hen therein, yet permit the small chicks to enter it at any point throughout its periphery.

In order to let the hen out of the 95 coop and her compartment, the latter is equipped in one side with an opening 4 closed by a pair of overlapping hinged doors 5 locked together by suitable means 5^a. The outer compartment 2 is likewise provided 100 with an opening directly opposite or in alignment with the opening 4 and it is closed by a sliding door 6 movable in guides 7. If desired, the door 6 may be equipped with a handle 8 to permit it to be raised and 105 lowered with facility. Attention is directed to the fact that the doors 5 are such a length that when swung open, their free edges contact the guides 7 as shown in Fig. 2, thereby limiting their movement and serving to 110

close the runway 3 so that the hen cannot enter the same. In order to hold the compartments in proper spaced relation, a plurality of hooks 8^a are provided, being pivotally connected to the outer compartment and having their hooked ends engaged with the adjacent horizontal wire of the inner compartment as shown.

As before stated, the outer sheet metal compartment is formed near its lower edge with a plurality of openings 9 which serve to permit the small chickens to pass in and out through them so that they can roam at large. If desired, the alternate openings 9 may be closed by isinglass windows 10. Furthermore, a circular closure 11, provided with a plurality of openings 12, may be employed for the purpose of opening and closing the passages 9. This closure is equipped 20 with a handle 13 to permit it to be moved to open and close the openings 9.

As before intimated, I so construct the sheet metal compartment that the attendant may have free access thereto. In carrying this out, I provide the roof 13 with a central opening 14 which is surrounded by a vertically disposed rim 15 having a plurality of closely spaced air inlet openings 16. A removable cover 17 serves to close the opening 14 and is equipped with a depending flange or ring 18 surrounding the rim 15, this flange 18 being equipped with openings 19 for registering with the openings 16, whereby the amount of air permitted to enter the 35 coop may be regulated or entirely shut off as the case may be. To facilitate removal and rotation of the cover, it is equipped with one or more handles 20.

In use, the mother hen is placed within 40 the wire compartment 1 and the doors are closed, being held in this position by the locking means shown. By confining the hen in this compartment, the chicks will be free to have unmolested use of the runway 3 and 45 there will be no chance of the hen injuring them. Yet, if they desire, the chicks can enter the inner compartment at any point throughout the circumference of the latter. They may also pass in and out of the openings 9 and roam about as they please. If it is desired to prevent them from passing in and out of the compartment 2 through these 50 openings, the slide 11 may be actuated to close the openings. As before indicated, the 55 air enters the compartment through the top of the outer compartment and it can be regulated to the desired degree by rotating the cover 17 to increase and decrease the amount of air passing through the air inlet 60 openings 16 and 19. Feed and water can be placed within the compartments by removing the cover 17. When it is desired to let the hen out of the coop, the doors 5 are swung open to the dotted line position indicated in Fig. 2 and the door 6 is elevated to

the dotted line portion indicated in Fig. 1. As before pointed out, the doors 5 when open prevent the hen from entering the runway 3 and molesting the small chicks.

A careful consideration of the description taken in connection with the drawings is sufficient to enable persons skilled in the art to which the invention relates to obtain a clear understanding of the same. Therefore, a more lengthy description is deemed unnecessary.

Since probably the best results may be obtained with the construction and arrangement herein shown and described, this construction and arrangement is taken as the preferred embodiment of the invention. However, slight minor changes coming within the scope of the subjoined claims may be resorted to.

I claim:

1. A chicken brooding coop comprising a substantially cylindrical housing closed at its top and having inlet and escape openings in its vertical wall adjacent the bottom thereof, and a wire cage or confining compartment for the hen arranged inside of the housing and permanently spaced from the wall of the latter to form a runway for the small chicks and to permit the latter to pass freely in and out between the wires of the cage.

2. A brooder coop comprising a substantially circular inner confining compartment for the hen, and an outer compartment surrounding the same and forming a runway between itself and the inner compartment for the chicks, said compartment being composed of spaced wires so as to confine the hen therein but permitting the chicks to pass freely into and out of it between the wires.

3. A chicken brooding coop made up of inner and outer spaced compartments, said inner compartment being designed for confinement of the hen and providing a runway between it and the wall of said outer compartment for the chicks, the walls of said compartments being formed with oppositely disposed outlet openings, and doors for closing said openings, the doors closing the inner compartment being hinged and adapted to swing across said runway to prevent the hen from getting into the latter.

4. A chicken coop having a substantially truncated conical roof, the apex opening of which is surrounded by a rim having air inlet openings formed therein, a substantially conical cover for said apex opening, said cover including a depending apertured ring spaced inwardly from its peripheral edge and contacting said rim so as to serve for permitting said air inlet openings to be closed or opened when the cover is rotated, the wall of said coop being formed with openings for passage of the small chickens, means for simultaneously closing all of said

openings, said wall being also formed with an opening closed by a door, a cage for confining a hen arranged inside of the coop and spaced from the wall thereof, being formed with an opening arranged opposite the last named opening and equipped with doors for closing said openings, said doors being

adapted to be swung across the space between the cage and coop for preventing the hen from entering this space. 10

In testimony whereof I have hereunto set my hand.

JULIA E. RISTY.
